Attorneys

UNITED STATES PATENT OFFICE.

JOHN D. CAMPBELL AND WILLIAM H. HOAG, OF SEA BRIGHT, NEW JERSEY.

ANTIRATTLER AND LOCKING DEVICE FOR BLINDS.

1,324,641.

Specification of Letters Patent.

Patented Dec. 9, 1919.

Application filed April 22, 1919. Serial No. 291,937.

To all whom it may concern:

Be it known that we, JOHN D. CAMPBELL and WILLIAM H. HOAG, both residing at Sea Bright, in the county of Monmouth and

5 State of New Jersey, both citizens of the United States, have jointly invented certain new and useful Improvements in Antirattler and Locking Devices for Blinds; and we do hereby declare the following to be a full, 10 clear, and exact description of the invention, such as will enable others skilled in the art to which it pertains to make and use the same.

Our invention relates to improvements in 15 an antirattler and locking device for blinds or shutters, and more particularly to a device for preventing the rattling of the pivoted slats and operating rod of a blind and the locking of the blind.

20 It is exceedingly annoying, especially at night, to hear the noise made by the rattling of the blinds throughout the house which is not conducive to the sleeping of a person in a normal condition much less one who 25 is nervous or sick and the object of our invention is to provide means to obviate or eliminate entirely all rattling or noise in connection with the blinds.

It further has for its object to provide 30 means for the purpose described which may be attached to the blind without disfiguring or marring the same.

It further has for its object to provide 35 means for attachment to the inside of the blind to take the place of the lath or batten usually placed on the outside of the blinds and nailed or otherwise secured to the window casing and which must be put on and removed from the outside of the blinds.

40 It further has for its object to provide means by which the blinds are held closed and afford protection when the sashes or windows are open.

It finally has for its object to provide 45 a device for the purpose described which is exceedingly simple, inexpensive and durable and compact in construction and easy and effective in use.

The invention consists in the several features and in the construction, combination and arrangement of features as more fully hereinafter described and claimed.

Referring to the drawings:—

Figure 1 is an inside face view of a pair 55 of blinds with our invention applied thereto.

Fig. 2 is a top plan view with the blinds partly in section and broken away.

Fig. 3 is a detail plan view of the device detached from the blinds.

Fig. 4 is a side view of one of the sliding devices for holding the clamping levers down.

Fig. 5 is a top plan view of one of the 60 sliding supports of the clamping levers.

Fig. 6 is a detail perspective view of one 65 of the clamping levers.

In the drawings in which similar reference characters denote similar parts throughout the several views, 1 and 2 represent a pair of blinds or shutters of well 70 known design and construction, each having a plurality of pivoted slats 3 and an operating rod 4 therefor pivotally connected to each of the slats.

The inner face of each of the blind stiles 75 5 and 6 of the blinds is provided with a screw 7 the head of which projects therefrom.

Our invention comprises a frame 8 made 80 preferably of some spring metal, but which may be made of any other suitable material desired, and which is provided with loops 85 9 and 10 shown as stirrup shaped one at each end and a narrow central or middle portion 11, the ends 12 of the frame terminating in the loop 9 and being provided with a sleeve 13 covering and securing the ends 12 together.

The narrow central portion 11 is provided 90 with supports or brackets 14 each support being provided with a clamping lever 15 pivoted thereto having a handle 16 and a claw 17 at its inner end, the lever being preferably formed of a single piece of sheet metal stamped into the desired shape.

95 The claws of the levers are adapted to be inserted under and engage the heads of the screws 7 and the levers moved downward against the pressure of the spring frame and the handles locked by being inserted in 100 sleeves 18 slidably mounted on the narrow central portion 11 of the frame 8.

The narrow central portion 11 of the frame 8 is normally curved or bowed upward and forms a spring arch 19 and when 105 the clamping levers are moved downward the spring arched portion is pressed downward by the levers until it is substantially in the same plane as the loops 9 and 10.

In use when it is desired to apply our 110

invention to the inside faces of the blinds, the loops 9 and 10 are placed against the operating rods 4 of the blinds, the claws of the clamping levers are engaged with the heads of the screws 7, the clamping levers turned on their pivots and moved downward causing the arched spring portion 19 of the frame to be depressed or pressed downward until the levers are in alinement therewith, when the sleeves 18 are slid along the frame and over the handles thus locking the handles against the tension of the spring arched portion 19 resulting in the blinds, the pivoted slats and operating rods being held and fastened so securely that all rattling is absolutely eliminated or prevented.

When it is desired to remove the device from the blinds it is only necessary to slide the sleeves on the frame until they disengage the handles 16 of the clamping levers, then move the levers upward and disengage the claws thereof from the screws 7 when the frame may be easily removed.

We do not wish to be understood as limiting ourselves to the specific details of construction and arrangement as herein described and illustrated, as it is manifest that variations and modifications may be made in the features of construction and arrangement in the adaptation of the device to the various conditions of use without departing from the spirit and scope of our invention and improvements. We therefore, reserve the right to all such variations and modifications as properly fall within the scope of our invention and the terms of the following claims.

What we claim is:—

- 40 1. In a device of the character described, a frame provided with pivoted clamping members, means for securing said frame to the blinds and means for locking said clamping members.
- 45 2. In a device of the character described, a frame, clamping members pivotally mounted thereon, means for securing said frame to the blinds and slidable means on said frame for locking said clamping members.
- 50 3. In a device of the character described, a frame provided with brackets, clamping members pivotally mounted on said brackets, means for securing said frame to the blinds and means for locking the clamping members.
- 55 4. In a device of the character described, a frame having an arched middle portion, means for securing said frame to the blinds, clamping members pivotally mounted on said arched middle portion and means for locking the said clamping members.

5. In a device of the character described, a frame provided with clamping members, means on the blinds adapted to be engaged by the clamping members for connecting them to the blinds and means for locking the clamping members to the said frame.

6. In a device of the character described, a frame having a spring middle portion, means for securing said frame to the blinds, clamping members pivotally mounted on said spring middle portion and means for locking said clamping members.

7. In a device of the character described, a frame having loops at each end and an arched spring middle portion, clamping levers, means for pivotally mounting the said levers on the said arched spring middle portion and means for locking the said levers.

8. In a device of the character described, a frame having a narrow middle portion and broad ends, clamping levers pivotally mounted on said narrow middle portion, means for connecting the said levers to the blinds and means for locking the said levers to the frame.

9. In a device of the character described, a frame made of one piece of material having loops at each end and an arched middle portion, brackets mounted on said arched middle portion, levers pivotally mounted on said brackets, and means slideable on the frame for locking said levers thereto.

10. In a device of the character described, a frame made of one piece of material having loops at each end and an arched spring middle portion, levers pivotally mounted on said arched spring middle portion, and means for locking said levers.

11. In a device of the character described, a frame made of one piece of material having stirrup-shaped loops at each end, an arched middle portion, levers pivotally mounted on said arched middle portion, and means for locking the said levers to the said frame.

12. In a device of the character described, a frame having loops at each end and an arched spring middle portion, levers pivotally mounted on said frame, and means slidably mounted on said frame for locking said levers.

13. In a device of the character described, a frame having an arched spring middle portion, brackets mounted thereon having pivotal levers, and means slidable on said frame for locking said levers.

In testimony whereof we have affixed our signatures.

JOHN D. CAMPBELL.
WILLIAM H. HOAG.
